EARLE C. ANTHONY, OF LOS ANGELES, CALIFORNIA.

ARTICLE FOR USE IN PRACTISING METHODS OF DISPENSING SERVICE.

1,260,619.

Specification of Letters Patent. Patented Mar. 26, 1918.

Application filed February 10, 1916. Serial No. 77,427.

To all whom it may concern:

Be it known that I, EARLE C. ANTHONY, a citizen of the United States, and resident of Los Angeles, California, have invented 5 certain new and useful Improvements in Articles for Use in Practising Methods of Dispensing Service, of which the following is a specification.

This invention relates to articles for use 10 in practising a method of dispensing service or labor in connection with the conduct of a business. It is particularly designed for use in the automobile business but may be used in other lines. 15 In the business of selling automobiles, as well as other machines that require more or less care and attention particularly during the first few months of their operation, it is found desirable by some dealers to render 20 free service to the purchaser of such machine for a certain length of time immediately succeeding the date of delivery of the machine. It is very desirable that that service, which with an automobile consists 25 in making adjustments, tuning up, etc., should be somewhat evenly distributed over the period of time during which it is to be rendered, or in other words, that the machine should be adjusted and tuned at reasonable 30 intervals during such period. It is also desirable that approximately the same amount of free service should be rendered or offered to each customer so that all will receive equal treatment.

35 In a large business it is difficult to keep proper and accurate account of the service rendered to a large number of customers, and it is one of the objects of the present invention to provide means for practising a 40 method of dispensing service of the above character whereby the service rendered will be accurately and readily accounted for, the purchaser of the machine will be encouraged to bring his machine to the seller's place of 45 business to receive the service which will keep his machine in better condition and consequently keep the purchaser better satisfied, and the service to various customers will tend to be more equally dispensed.

50 Other objects of the invention will appear from the following description, taken in connection with the drawings which form a part of this specification, and in which:

Figure 1 is a plan view of a book embodying the invention;

Fig. 2 is an edge view of the book shown in Fig. 1; and

Figs. 3, 4 and 5 are views of separate leaves of the book.

As shown in the drawings, which are 60 merely illustrative of the inventive idea, the invention consists of a coupon book comprising a body portion and a plurality of separable coupons, the body portion having a description of a machine, such as an automobile, upon which service is to be performed and having also an identification symbol for the particular machine, and the several coupons having, 1st, a value designation such as the number of minutes or hours 65 of work or labor for which the coupon will constitute payment, or the amount in dollars and cents which the coupon represents, 2nd, an identification symbol which corresponds to the symbol on the body portion of the book, and which is the same on all the coupons of the book, and 3rd, a period of time designation which identifies the coupon, for instance, with a certain month of the year in which the machine is 70 sold, these periods of time differing on different coupons in the same book, so that the use of the coupons will be distributed in point of time and the coupons may not be used cumulatively. 75

Thus in Figs. 1 and 2, the book B may comprise the body portion or cover 10 and leaves 11 of several coupons each. The cover and leaves or coupons are bound together as by fasteners 12, and each of the coupons 80 may be detached as by means of the perforations or scoring 13.

Upon the body portion or cover of the book is a description of a machine upon which service is to be rendered. In Fig. 1, 95 a sample of a description is given at 14 as follows: "Car, Packard '38', Body, Touring car, Year 1915, Car No. 78123." Any additional descriptive matter and advertising words may be used, and if desired the 100 number of hours of labor comprised within the book may be designated thereon, as shown at 15 in Fig. 1. The body portion also has an identification symbol 16 shown in the upper right hand cover of Fig. 1, this 105 being the book number as follows "P 100 B." Any suitable symbol may be used.

One of the coupons is illustrated in full at the left in Fig. 3. It will be understood that all of the printed matter within the 110

wavy line 17 in Fig. 3 forms a part of each of the several coupons of the book. Each of the coupons also has a value designation 18; as shown this designation is "½ hour service 5 labor". It may be otherwise expressed to indicate the value of the coupon to the holder. Each coupon has an identification symbol 19 which corresponds to the identification symbol 16 of the body portion, being 10 shown as follows: "P. 100 B". The coupons are all alike in this respect. Each coupon has a period of time designation 20, shown as a given month of a certain year. This indicates the time within which the 15 particular coupon may be used, and in this respect some of the coupons differ from others. For instance, in Fig. 3, each of the five coupons on the leaf there illustrated has a time designation of "Sept. 1915", indicating 20 that those coupons are good in that month only, while in Fig. 4 the coupons are each dated "Oct. 1915", the succeeding month, and in Fig. 5 they are dated "Nov. 1915". It will be understood that several 25 leaves for each of several successive months may be used in a single book, to make up the required number of hours of service that it is intended shall be rendered for a particular machine. Thus the coupons are so dated 30 that the total of the individual periods of time covered by the several coupons will be continuous from one definite date to another to distribute the use of the coupons over a definite total period of time, and thus prevent 35 their use in a lump, or cumulatively. By this device a purchaser of a machine is not so likely to run the machine without the technical attention that it should have, and he cannot save all of his coupons until close 40 to the expiration of the time within which free service is rendered and use them all for a general overhauling of the machine. This is of the utmost advantage in the business of dispensing free service.

45 In addition to the printed time designation above referred to, the several leaves or coupons may be variously colored to more readily identify their time designation or to form an additional means of designating 50 the periods of time. Thus, all of the Sep-

tember coupons may be colored blue, the October coupons red, and the November coupons purple, as indicated in the drawings by the cross hatching.

In the use of the books it will be understood that one of them, made up of the desired number of coupons or leaves and with the proper description of the machine on the body portion, is delivered to the purchaser of a machine at the time the machine 60 is delivered, the first coupons in the book having the period of time beginning approximately on that date and the others following as above explained. The purchaser brings the machine in to the seller's place of 65 business or otherwise receives the desired service in the way intended, and the coupons are torn off by the seller in payment for the labor performed. These coupons are filed with the other records of the particular machine and thereby assist in keeping the seller constantly advised of the amount of adjusting and tuning that is required for 70 the machine in question.

Only one form of the invention has been 75 shown and described but it will be apparent that various changes may be made from the form shown without departing from the spirit or scope of the invention.

Having thus described my invention, what 80 I claim and desire to secure by Letters Patent is:—

A coupon book for use in practising a method of dispensing service, said book comprising a body portion and a plurality of 85 separable coupons, said body portion having indicia fully identifying a particular machine upon which service is to be performed, said coupons having 1st, a value designation, 2d, a period of time designation, and 3d, indicia serving to identify each of said coupons with the particular machine; the period of time designation of one of said coupons differing from that of another whereby by the use of the coupons is distributed in 90 95 point of time and is rendered non-cumulative.

In testimony whereof I affix my signature.

EARLE C. ANTHONY.
